UNITED STATES PATENT OFFICE.

FREDERICK W. ANDREW, OF BROOKLYN, NEW YORK, ASSIGNEE TO EISEMANN MAGNETO CORPORATION, OF BROOKLYN, NEW YORK, A CORPORATION OF NEW YORK.

DUAL MAGNETO IGNITION SYSTEM FOR GAS ENGINES.

Application filed November 25, 1922. Serial No. 603,319.

To all whom it may concern:

Be it known that I, FREDERICK W. ANDREW, a citizen of the United States, and a resident of the city of New York, 5 borough of Brooklyn, county of Kings, and State of New York, have invented certain new and useful Improvements in Dual Magneto Ignition Systems for Gas Engines, of which the following is a specification.

10 My invention relates to electric ignition systems for gas engines, and its object is to provide a dual magneto ignition system especially useful in starting heavy gas engines.

15 It is a well known fact that gas engines designed for heavy work—as on road tractors, for instance—cannot be turned over when cold in the ordinary way. Hand-cranking and battery starters are out of 20 the question.

To overcome these and other difficulties, I have invented an ignition system which functions with certainty in producing the requisite electric sparks for starting and 25 running gas engines, particularly engines of heavy construction, where ordinary starting devices are useless or unreliable. Briefly stated, my new ignition system or apparatus comprises a hand-operated high-tension 30 starting magneto, a high-tension running magneto driven by the engine, and a high-tension switch operated by the starting magneto for automatically controlling the ignition circuits of the two magnetos. These 35 circuits are independent of each other, except that they may (but need not) utilize a common distributor in a multi-cylinder engine. The high-tension switch is preferably mounted on the starting magneto and 40 operatively connected to the armature shaft thereof. For operating the starting magneto, I prefer a spring mechanism adapted to be placed under tension (as by moving a handle) and automatically released to impart an accelerated rotation to the armature 45 of the starting magneto, whereby the necessary starting spark is produced. The high-tension switch normally closes the ignition circuit of the starting magneto, but after 50 the armature has been rotated to produce the required spark for starting, the switch is automatically moved to open the starting circuit, whereupon the running magneto takes hold, as we say, to operate the engine.

In one arrangement of circuit connections, 55 the high-tension switch automatically closes the ignition circuit of the running magneto right after the engine has started and before the distributor arm of the running magneto is in position to connect the spark plug 60 next to be fired. There are several ways of connecting the two magnetos in circuit, as will later appear.

In the accompanying drawings I have shown a preferred embodiment of my invention as actually practised.

In these drawings,

Figure 1 is a side view, partly in section, of a high-tension starting magneto for use in my new ignition system;

Fig. 2 is a right end view of the magneto shown in Fig. 1, the handle for operating the starting mechanism being in normal position, the same as in Fig. 1;

Fig. 3 is a cross-section approximately 75 on line 3—3 of Fig. 1, showing the rotary member of the high-tension switch and its gear connections with the armature shaft, the switch being in normal or starting position to close the circuit of the starting magneto;

Fig. 4 is a view similar to Fig. 2, with certain parts in section to show the inside starting mechanism and with the handle in thrown-over position;

Fig. 5 shows an enlarged cross-sectional view of the hand-actuated mechanism for operating the starting magneto, the section being taken approximately on lines 5—5 and 5'—5' of Fig. 2, with the handle in substantially vertical position;

Fig. 6 is a cross-section approximately on line 6—6 of Fig. 1, looking in the direction of the arrows;

Fig. 7 is a detached view, partly diagrammatic, showing the high-tension switch in position to close the ignition circuit of the running magneto;

Fig. 8 is a detached inside view of the insulating block which carries the contacts of the high-tension switch mounted on the starting magneto;

Fig. 9 is a view, partly in section and partly broken away, of a high-tension running magneto adapted for use in my ignition system;

Fig. 10 is a detached inside view of the distributor block shown in section in Fig. 9;

Fig. 11 is a diagram of an arrangement of circuit connections of the starting and running magnetos, in which a four-cylinder engine may be started on any cylinder;

5 Fig. 12 is a diagram of more simplified circuit connections, by which a four-cylinder engine is started on one cylinder only; and

10 Fig. 13 is a diagram of circuit connections for a one-cylinder engine.

The high-tension starting magneto shown in Fig. 1 may be of any approved type as regards the armature and field construction, so I need only say that a suitable armature 15 of inductor A is mounted to rotate or oscillate between the poles of a field magnet M. At the left end of this magnet is casing C, which contains the usual timer and interrupter. As the function of these parts is 20 well known to the experts in this art, no further illustration and description thereof are necessary. For convenience, I will designate the starting magneto as a whole by SM.

On the right end (as viewed in Fig. 1) of 25 the armature shaft 1 of the starting magneto is mounted the mechanism for operating the magneto by hand. In the present instance, this starting mechanism is in certain respects similar to the impulse starter shown in my 30 Patent No. 1,324,199, dated June 1, 1920, and is adapted to produce an accelerated rotation of the armature. This starting mechanism is shown in Figs. 1, 2, 4, 5 and 6; to which I will now refer in detail.

35 On the projecting end of armature shaft 1 is rigidly mounted a hub 2 on which is fixed a disk 3, which may be referred to as the driven member of the starting mechanism. As a convenient means for holding disk 3 on hub 2, I have shown the hub with an off-set circular flange 4 adapted to be bent over against the beveled edge 4' of the disk after the latter is on the hub. The disk 3 is thus rigidly connected to shaft 1. A cup-shaped cylindrical casing 6 is rotatably mounted on hub 2 and is held in place in any suitable way, as by a flanged sleeve 6 which projects outwardly from the hub, as best shown in Fig. 5. A nut 7 holds hub 2 40 and sleeve 6 in position on the armature shaft. The outer periphery of member 5, which may be called the driving cup, extends into a circumferential recess 8 formed in disk 3, so that the member 5 finds adequate 45 support on disk 3 and hub 2. On the peripheral edge of driving cup 5 is a lug 5', which projects into an arcuate clearing slot or cut-away section 3' formed in the disk 3. In Fig. 6, this clearing slot extends from 50 shoulder 3^a to shoulder 3^b. The purpose of lug 5' and these shoulders will presently be explained.

Inside of the chamber formed by members 3 and 5 is a coil spring 9. The outer end of 55 this spring is secured to a lug 10 secured by

rivets 10' (or otherwise) to the cylindrical wall of driving cup 5. The inner end of spring 9 is fastened to hub 2 in any suitable way, as by entering a slot 11. It will thus be seen that the inner end of spring 9 is in effect secured to the armature shaft, while the outer end is connected to the rotatable driving member 5. When the parts of the starting mechanism are first assembled, coil 60 spring 9 is placed under initial tension and normally holds lug 5' of driving member 5 against shoulder 3^a of disk 3, as shown in Fig. 6.

A suitable handle 12 is fastened to the driving cup 5 for turning the same to wind 65 up the spring 9. Handle 12 is secured to the periphery of the driving cup 5 in any convenient manner, as by rivets 13 or otherwise. On a plate 14, fixed to studs 15 of the magneto frame, are rigidly mounted two 70 stops 16 and 17, arranged as shown in Figs. 2 and 4, for limiting the throw of the handle by engaging a projection 18 at the base of the handle.

In order to place spring 9 under tension 75 when the handle 12 is turned clockwise from the position shown in Fig. 2, it is clear that the armature shaft must be held stationary. For this purpose, I provide a fixed catch 19 80 preferably formed on plate 14. If this plate is made of sheet metal, catch 19 may conveniently be formed by striking up the metal and bending it into proper position. On the rear side of disk 3 is a stud 20 on which is pivoted a gravity pawl 21, as best shown in 85 Fig. 6. At its free end, pawl 21 has a tooth 22 arranged to bear normally against catch 19 and thereby hold the disk 3, and therefore the armature shaft 1, against rotation. Pawl 21 is also provided at its free end with 90 an extension 23 arranged to lie over the periphery of driving cup 5. A guide lug 24 95 may be provided for the free end of pawl 21, as shown in Figs. 1 and 6. This guide lug is secured to the rear side of disk 3 by rivets 100 25. It is clear from the foregoing that as long as the tooth 22 of pawl 21 engages the fixed catch 19, armature shaft 1 of the starting magneto is held against rotation.

105 I will now describe the means for automatically releasing the armature shaft when handle 12 is thrown forward to place the coil spring 9 under tension. On the periphery of driving cup 5 is formed a cam 26. As 110 the member 5 may be stamped out of sheet metal, cam 26 is easily formed by simply upsetting the metal at the proper point. As 115 seen from Fig. 1, the extension 23 of pawl 21 lies in the path of cam 26. When handle 12 is moved clockwise from the position 120 shown in Fig. 2, spring 9 is placed under tension, because disk 3 is held stationary by the engagement of pawl 21 with catch 19. As 125 cam 26 rides under extension 23 of pawl 21, it moves the pawl outwardly to disen-

gage tooth 22 from catch 19. This automatically releases the tensioned spring, which imparts to the armature an accelerated rotation sufficient to produce a spark in the ignition circuit of the magneto, as those skilled in the art well understand. Forward rotation of the handle 12 continues until the projection 18 thereof strikes stop 17. The handle remains in actuated position until thrown back by the operator.

In order to hold handle 12 and the connected parts against rattling or accidental movement in either position of the handle, I provide the handle with a pin 27 adapted to be pressed inwardly by a weak spring 28. Plate 14 is provided with a pair of small holes 29 and 30, arranged as shown in Figs. 4 and 2, respectively. When handle 12 is in normal position, the inner rounded end of pin 27 is pushed slightly into hole 29. This frictional contact holds the handle firmly in position, and yet permits the pin to be readily forced out of the hole by a slight pressure on the handle. Similarly, when the handle reaches the end of its forward movement, pin 27 snaps into hole 30. Preferably the location of holes 29 and 30 is such that there is a slight clearance between the handle and stops 16 and 17, respectively, when the handle is held by pin 27 in either position.

The armature shaft 1 of the starting magneto SM has rigidly mounted thereon a small gear or pinion 31, which is permanently in mesh with a large gear 32. The gear ratio here is two to one, but this is merely a matter of convenience, as any suitable gear ratio may be used. Gears 31 and 32 are preferably made of non-metallic material, such as bakelite canvas or similar substances. Gear 32 is secured to a shaft 33 by a screw 34 or otherwise. A thrust washer 34' may be interposed. Gear 32 is enclosed by a casing H, which may be integral with the magneto frame. It will be understood, of course, that the magneto frame or casting is of non-magnetic material. Shaft 33 is journalled in a bushing 35 mounted in a housing 36, which may conveniently be cast as a part of the magneto frame. Bushing 35 is provided at its outer end with a flange 37 adapted to fit into a recess 36' in the housing 36. To effect proper engagement of gears 31 and 32, bushing 35 is made eccentric, as indicated in dotted lines in Fig. 2. The outer edge of bushing 35 is provided with a pair of diametrically opposite notches 38, into which a tool is inserted for turning the bushing in such position that the teeth of gear 32 will properly mesh with the teeth of gear 31. The eccentric bushing 35 is held in adjusted position by a spring plate 39 secured on housing 36 by screws 40, or otherwise. The metal of plate 36 is upset inwardly at several points as indicated at

41 in Fig. 4. These upset points form prongs which press against the flange 37 of bushing 35 and thus hold the same in adjusted position. If desired, plate 39 may have a hook-like extension 39', which simply hooks over one of the screws and permits ready swinging of the plate into open and closed position.

Gear 32 has secured to the outer face thereof an insulating disk 42 which is removably fastened by suitable means, such as screws 43. Disk 42 carries an arc-shaped conducting strip or switch member 44, which is preferably embedded so as to lie substantially flush with the outer surface of the disk, as indicated in Fig. 1.

On the frame of the starting magneto is mounted a recessed insulating block 45, the form and construction of which are shown in Figs. 1 and 8. This block is preferably pressed or molded out of a suitable plastic composition, of which there are several on the market. Block 45 is so shaped that the lower edge 46 thereof rests on the upper straight edge of a plate 47 secured to the magneto frame, as shown in Fig. 1. A spring lever 48 is pivoted at 49 to a stud 50 on the magneto frame, and the free end of the lever is adapted to bear against block 45 when the latter is in position on the machine. By simply swinging the lever 48 out of engagement with block 45, the latter is free to be removed from the magneto. As seen in Fig. 1, the circumferential edge 45' of block 45 fits against the adjacent edge of casing H, thus forming a practically closed chamber for the parts inside.

Block 45 carries a spring-pressed contact 51 adapted to bear continuously on collector ring 52 when the block is in position on the magneto. Contact 51, commonly called a collector brush, is usually formed of carbon. A metallic strip or wire 53 is embedded in block 45 and connected at its inner end to the metallic bushing 54 in which brush 51 is mounted. This is shown in Fig. 1. Referring to Fig. 8, it will be seen that the block 45 is on its inner face provided with contacts 55, 56 and 57, similar in construction and mounting to contact 51. A wire 53, connected at its inner end to brush 51, is at its other end electrically connected to contact 55. A conductor 58, passing through an opening in block 45, is electrically connected to contact 56, and a conductor 59 is similarly connected to contact 57. As will be explained later, conductors 58 and 59 are in the high-tension circuits of the starting and running magnetos, but conductor 59 is never in the high-tension circuit of the starting magneto. Contacts 55, 56 and 57 are arranged concentrically with respect to the arcuate connecting strip 44, as indicated in Figs. 3 and 7.

It is thus clear that contacts 55, 56 and 57

57 and connecting strip 44 constitute a high-tension switch controlled by the armature of the starting magneto. When handle 12 is in normal position, as shown in Fig. 2, strip 44 is in position to connect contacts 55 and 56. We shall call this the normal or starting position of the switch, because in that position it closes the ignition circuit of the starting magneto, as will presently be explained. When the handle is moved into the position shown in Fig. 4 to operate the starting magneto through the spring mechanism previously described, disk 42 is rotated clockwise (as viewed in Fig. 3) into the position shown in Fig. 7, where the switch member 44 connects contacts 56 and 57 and thereby closes the ignition circuit of the running magneto. The position of the high-tension switch as shown in Fig. 7 may therefore be called its running position.

In Fig. 9, I have shown a portion of a running magneto, which I will indicate as a whole by RM. I have not deemed it necessary to illustrate any details of construction of this magneto beyond what is shown in Fig. 9, for the reason that any suitable type of high-tension magneto may be employed, and so I want to be understood that magneto RM is to be considered as merely illustrative, except for the novel form of distributor mounted thereon.

Magneto RM is driven from the engine shaft through any suitable connection, preferably through an impulse starter, an example of which is shown in my Patent No. 1,324,999, dated June 1, 1920.

The armature shaft of the running magneto has fixed thereon a small gear or pinion 60 in mesh with a larger gear 61 mounted on a shaft 62, which is rotatably supported in the magneto frame in any convenient manner. Shaft 62 may be supported in the same way as shaft 33 of gear 32, previously described. Gears 60 and 61 are preferably of insulating material, such as bakelite canvas or other similar composition. To the outer face of gear 61 is attached an insulating disk 63, which carries a metallic connecting piece or switch arm 64. As shown in Fig. 9, member 64 is preferably embedded in the disk, so as to lie flush with the outer surface thereof. The general shape of switch arm 64 is indicated in dotted lines in Fig. 11.

The switch arm 64 constitutes the rotary part of the distributor, the stationary part of which comprises an insulating block indicated as a whole by 65. This block, which may be pressed or molded out of a suitable composition, is adapted to rest on top of a plate 67 secured to the magneto frame. Suitable means, such as a spring lever 68 pivoted at 69, holds block 65 firmly in position on the machine.

The distributor block 65 carries six contacts indicated by 70, 71, 72, 73, 74 and 75. In Figs. 9 and 10, these contacts are shown in the form of cylindrical carbon brushes, as they are called, each mounted in a metallic bushing 76 and pressed outwardly by a spring 77. This form of carbon brush is well known in the art and I have shown it merely as a matter of convenience.

In the body of distributor disk 65 are formed six openings, indicated in Fig. 10 by dotted lines 78. One of these openings is shown sectionally in Fig. 9. Into the openings 78 extend insulated electric conductors 79, 80, 81, 82, 83 and 84. Into each conductor opening 78 extends a screw 85 for holding the inner end of the conductor clamped in good electrical contact with the associated carbon brush. Fig. 9 shows how conductor 81 is held in electric contact with brush 71. In a similar manner, conductor 79 is connected to contact 74, conductor 80 is connected to contact 72, conductor 82 is connected to contact 73, conductor 83 is connected to contact 70 through a metal strip or wire 86, and conductor 84 is connected to contact 75. As seen in Fig. 9, the connecting strip or wire 86 is embedded in the body of the insulating disk. Brush or contact 70 is arranged to bear continuously on the collector ring 87 of the magneto to collect the current from the secondary or high-tension winding, as will be understood.

In the casing K of running magneto RM are mounted a timer and interrupter of suitable construction. As these devices do not in and of themselves form part of my invention, and as their function is well understood in the art, I need not go into any details concerning them.

I will now refer to Fig. 11 to explain the circuit connections of the two magnetos when a distributor like that shown in Figs. 9 and 10 is used. In Fig. 11, the starting magneto SM is diagrammatically indicated by the primary winding P and the secondary winding S. Similarly, the running magneto RM is diagrammatically represented by the primary winding P' and the secondary winding S'. One end of primary winding P is grounded at 88 and the other end at 89. The circuit of the primary winding includes the usual breaker contacts 90 and a condenser 91 shunted across the contacts. One end of the secondary or high-tension coil S is connected to one end of the primary coil P, as indicated by a conductor 92, and the other end of the secondary winding is connected by a lead or conductor 93 to the collector brush 51 of the high-tension switch.

In the running magneto RM, the primary winding P' is at one end grounded at 94 and the other end is grounded at 95 through the breaker contacts 96, which are shunted by a condenser 97. A suitable hand-

operated short-circuiting switch W may be provided for cutting the breaker contacts out of circuit and thereby short-circuiting the primary winding P' . The secondary or 5 high-tension winding S' is at one end connected to the primary coil, as indicated by a conductor 98. The other end of the secondary winding is connected to the collector brush 70, as diagrammatically represented 10 by a conductor 99.

Conductor 79 connects brush 74 to spark plug 100, conductor 80 connects brush 72 to spark plug 101, conductor 82 connects brush 73 to spark plug 102, and conductor 15 84 connects brush 75 to spark plug 103. The brush 71 of distributor block 65 is electrically connected to contact 56 of the high-tension switch, as diagrammatically indicated by conductors 81, 104 and 58, in Fig. 11. 20 In practice, of course, there will be a single conductor leading from contact 56 to contact 71. The contact 57 of the high-tension switch is electrically connected to collector brush 70 of distributor block 65, as 25 diagrammatically indicated by lines 59, 105 and 83, in Fig. 11.

The operation of my dual magneto ignition system will now be understood, but for the sake of clearness I will briefly describe 30 the same as follows: Let us assume that the operator wishes to start the gas engine, in this case a four-cylinder engine. The handle 12 of the starting mechanism is in normal position, as shown in Fig. 2, and the rotary strip 44 of the high-tension switch is 35 in normal or starting position to connect contacts 55 and 56. To actuate the starting mechanism, the operator throws the handle over to cause accelerated rotation of the 40 armature by the spring 9, as previously explained in detail. At the moment of sparking, the switch arm 44 is still in position to connect contacts 55 and 56, as indicated in Fig. 11. Let us assume that when the 45 sparking occurs the rotary switch arm 64 of the distributor of the running magneto is in position to connect brush 71 with brush 72. The ignition circuit of the secondary winding S of the starting magneto 50 may be traced as follows: From coil S through conductor 93, contact 51, conductor 53, contact 55, through switch arm 44 to contact 56, through conductors 58, 104 and 81 to brush 71, through switch arm 64 to 55 brush 72, and from there through conductor 80 to spark plug 101. After the sparking has occurred and just before the operating handle 12 reaches the end of its forward throw, the rotary movement of the starting 60 armature, under the action of spring 9 throws the switch member 44 into position to connect contacts 56 and 57, thereby breaking the starting circuit and closing the ignition circuit of the running magneto. I 65 might explain here that when the handle is

moved forward to tension the spring, while the disk 3 and connected parts are held stationary, the moment of release of spring 9 by cam 26 occurs just before the lug 5' of driving cup 5 reaches the end of clearing 70 slot 3', as indicated by the dotted lines α in Fig. 6. As the handle is left in its actuated position, in which it is firmly held by pin 27, the switch member 44 remains in position to maintain the running circuit closed. 75

When the operator wants to stop the engine, all he has to do is to close the short-circuiting switch W of the running magneto, or he may throw back the handle from the position shown in Fig. 4 to the position 80 shown in Fig. 2, whereby the armature shaft is rotated sufficiently to swing the switch arm 44 back into the position shown in Figs. 3 and 11, thus breaking the ignition circuit of the running magneto. This reverse movement of the armature is brought about by the lug 5' of driving cup 5 engaging the shoulder 3 α of disk 3, whereby the members 5 and 3 are coupled together and turn backward as a unit to restore the starting mechanism to normal position. 90

As previously stated, my new ignition system is particularly useful in starting large gas engines. I have successfully operated my new system on road-tractor engines of 95 the four-cylinder type. These were unusually heavy engines, having cylinder dimensions of 7" by 9". In starting such an engine with my system, the preliminary procedure is about as follows: A crowbar or similar instrument is inserted through the spokes of the engine flywheel and by means of the leverage thus obtained the flywheel is turned over until one of the cylinders is approximately 35° past top dead center in a 100 firing position. The cylinders are now primed with gasoline, and air under compression is pumped into the cylinder which is in firing position. Due to the fact that cylinders of gas engines cannot be made 105 theoretically tight, they lose this compression rather fast, and I have found from actual experience that in order to fire the compressed mixture in the cylinder it is necessary to send a spark into the cylinder at the very instant of stopping the pumping of air into the cylinder. Therefore, as soon as the operator has pumped sufficient air into the cylinder, he simply throws over the handle 12 of the starting magneto and the 110 operation of starting the engine is instantly completed. As soon as the engine has started, switch arm 44 is quickly moved by spring 9 to close the running circuit, as previously explained. As the engine is at that 115 moment moving comparatively slowly, the quicker movement of switch arm 44 closes the circuit connections of the running magneto before the distributor arm 64 is in position to connect the spark plug next to be 120 125 130

6 fired. When the running magneto first takes hold, the engine may not rotate with sufficient speed to generate a sparking current in the running magneto. However, 5 this low speed of the engine is sufficient to operate the impulse starter of the running magneto and thereby cause an accelerated movement of the armature to generate an ignition current. Then, when the engine 10 has attained full speed, the impulse starter acts simply as a coupling between the engine and the armature of the running magneto, as will be apparent to those familiar with this art. Thus, it is clear that in my system, 15 as soon as the starting spark has taken place, the function of operating the engine is transferred directly and solely to the running magneto. The length of switch arm 44 is such that the starting circuit is broken 20 before the running circuit is closed, as may be seen by comparing the positions of switch arm 44 in Figs. 3 and 7. As will be apparent from the foregoing, the oscillating starting mechanism produces a single spark during each oscillation. If the mixture in the 25 engine cylinder is in a firable condition, one spark will start the engine, so that only one forward throw of the handle 12 is necessary.

Fig. 12 shows a somewhat simplified arrangement of circuits. In this diagram, I use the same reference characters as in Fig. 11 to indicate corresponding parts, so I need not go over those details again. The running magneto RM of Fig. 12 has the standard form of distributor used with a four-cylinder engine. This distributor, diagrammatically represented at D, comprises a stationary insulating block and a rotary disk. This is the usual construction, as will be understood. The insulating block carries four contacts or carbon brushes 105, 106, 107 and 108, electrically connected to spark plugs E¹, E², E³ and E⁴, respectively. The collector brush 109 at the lower end of the 45 block takes the high-tension current from the collector ring of the magneto. This electrical connection is indicated in Fig. 12 by a conductor 110. The distributor block also carries a central brush or contact 111, 50 which is connected to brush 109 by a conducting strip or wire 112, usually embedded in the material of the block. The rotary disk of the distributor carries a metal segment 113, so arranged as to connect the central brush 111 with any of the four contacts 105, 106, 107 and 108. The foregoing are the usual electrical connections between a high-tension magneto and a four-cylinder engine.

60 Now, let us say that we want to start the engine on spark plug E³. All we have to do is to connect contact 56 of the high-tension starting switch to any point in the circuit of spark plug E³, as indicated diagrammatically by a conductor 114 leading from contact 56 to point 115. This point is intended to represent any point of connection between distributor brush 107 and spark plug E³. Thus, the ignition circuit of the starting magneto is closed through contacts 55 and 56 of the high-tension switch, through the single conductor 114, and through the selected spark plug E³.

It is clear that the circuit connections of Fig. 12 are simplified as compared with those of Fig. 11. Only one connection leads from the starting switch and no special form of distributor on the running magneto is necessary. Also, the high-tension switch need only have contacts 55 and 56, the third contact 57 used in the circuit of Fig. 11 being superfluous. The ignition circuit of the running magneto is in this case wholly independent of the starting switch, and is always in condition to take hold of the engine after the same has been started by the starting magneto. It will be understood that here, as in the arrangement of Fig. 11, when the handle of the starting mechanism is thrown over to start the engine, the spring-impelled switch arm 44 breaks the starting circuit before the next spark plug is fired by the running magneto.

Of course, the connections of Fig. 12 require the engine to be started always on the same cylinder, but this is not a disadvantage in actual practice. For instance, in the big engines on road tractors, the air-pump used in starting is connected to one cylinder only, and the connection 114 is assumed to lead to the spark plug of that cylinder.

In Fig. 13 we have a circuit arrangement similar to that of Fig. 12, as used with a one-cylinder engine. The spark plug U of the engine is connected to contact 56 of the starting switch by conductor 116. No distributor is needed here and the spark plug is directly connected to the secondary winding of the running magneto, as indicated by a conductor 117. Otherwise, what has been said about the circuit connections in Fig. 12 applies to Fig. 13.

Although I have herein set forth certain structural details in connection with the starting and running magnetos, I will have it understood that such details are to be regarded merely as illustrative and in no sense as limitations. It is obvious that in the broad aspect of my invention, changes and alterations in the construction of the starting mechanism, the high-tension switch on the starting magneto, the distributor of the running magneto and other structural features, may be resorted to without departing from the scope of the invention as defined in the appended claims. As indicated in Figs. 11, 12 and 13, it is clear that my invention is equally applicable to gas en-

gines having one or more cylinders. I might add that when I use the term "gas engine" in the description and claims, I mean broadly an internal combustion engine 5 of any type, class or construction.

For the sake of brevity, I use the expression "starting circuit" to indicate the ignition circuit of the starting magneto, and by "running circuit" I mean the ignition circuit 10 of the running magneto.

I claim as my invention:

1. In a dual magneto ignition system for gas engines, a high-tension running magneto driven by the engine, a high-tension 15 starting magneto, means for electrically connecting said magnetos to the spark plugs of the engine, the high-tension circuits of the two magnetos being independent of each other, hand-actuated mechanism for operating the starting magneto, a switch for normally closing the starting circuit and for opening said circuit when the switch is in actuated position, the running circuit being open when said switch is in normal position 20 and being closed when said switch is in actuated position, and means for operatively connecting said switch to said mechanism in such a way that the actuation of said mechanism to operate the starting magneto automatically throws said switch from starting 25 to running position after the starting ignition takes place.

2. In a dual magneto ignition system for gas engines, a high-tension running magneto 30 driven by the engine, a high-tension starting magneto, means for electrically connecting said magnetos to the spark plugs of the engine, the high-tension circuits of the two magnetos being independent of each other, a switch mounted on the starting magneto and operatively connected to the armature shaft thereof, said switch normally closing the starting circuit, connections whereby the running circuit is open when said switch is 35 in normal position, and hand-operated spring mechanism for imparting to the armature shaft of the starting magneto an accelerated rotary movement to produce a spark for starting the engine, said rotary movement of the starting armature automatically throwing said switch into position to open the starting circuit and to close 40 the running circuit.

3. In a dual magneto ignition system for gas engines, a high-tension running magneto driven by the engine, a high-tension starting magneto, means for electrically connecting said magnetos to the spark plugs of the engines, the high-tension circuits of the two magnetos being independent of each other, a switch mounted on the starting magneto and operatively connected to the armature shaft thereof, said switch normally closing the starting circuit, connections whereby the running circuit is open 50

when said switch is in normal position, a handle movably mounted on the armature shaft of the starting magneto, and spring mechanism for releasably connecting said handle to said armature shaft, so that a forward movement of the handle causes said mechanism to impart an accelerated rotation to said armature shaft to produce a spark for starting the engine, said rotary movement of the starting armature automatically throwing said switch into position to open the starting circuit and to close the running circuit. 70

4. In a dual magneto ignition system for gas engines, a high-tension running magneto adapted to be driven by the engine, a distributor mounted on said magneto and electrically connected to the spark plugs of the engine cylinders, said distributor having a rotary contact member driven by the magneto shaft, means for connecting said distributor in the high-tension circuit of the running magneto, a high-tension starting magneto electrically connected to the rotary contact member of said distributor, 80 hand-actuated mechanism for operating the starting magneto, and a switch operated by the armature shaft of the starting magneto for controlling the high-tension circuits of the two magnetos. 85

5. In a dual magneto ignition system for gas engines, a high-tension running magneto adapted to be driven by the engine, a distributor mounted on said magneto and electrically connected to the spark plugs of the engine cylinders, said distributor having a rotary contact member driven by the magneto shaft, means for connecting said distributor in the high-tension circuit of the running magneto, a high-tension starting magneto electrically connected to the rotary contact member of said distributor, hand-actuated mechanism for operating the starting magneto, a switch mounted on the starting magneto for controlling the high-tension circuits of the two magnetos, said switch comprising a stationary member 100 carrying contacts and a rotary member arranged to connect said contacts electrically, and means for operatively connecting said rotary member to the armature shaft of the starting magneto. 105

6. In a dual magneto ignition system for gas engines, a high-tension starting magneto, hand-actuated oscillating mechanism for operating said magneto to start the engine, a high-tension running magneto operatively connected with the engine, the high-tension circuits of the two magnetos being independent of each other, and a switch controlled by said mechanism for controlling the high-tension circuits of the two magnetos. 110

7. In a dual magneto ignition system for gas engines, a high-tension starting mag- 115

7. neto, hand-actuated mechanism for operating said magneto to start the engine, a high-tension running magneto operatively connected to the engine, the high-tension circuits of the two magnetos being independent of each other, and a switch mounted on the starting magneto and operated by the armature shaft thereof for controlling the high-tension circuits of the two magnetos.
8. In a dual magneto ignition system for gas engines, a high-tension starting magneto, a handle movably mounted on the armature shaft of said magneto and capable of forward and return movement, spring mechanism for releasably connecting said handle to said armature shaft, so that a forward movement of said handle causes said mechanism to impart an accelerated rotation to said armature to produce a spark for starting the engine, a high-tension running magneto operatively connected to the engine, and a switch controlled by the armature shaft of the starting magneto for controlling the high-tension circuits of the two magnetos.
9. In a dual magneto ignition system for gas engines, a high-tension starting magneto, a handle movably mounted on the armature shaft of said magneto and capable of forward and return movement, spring mechanism for releasably connecting said handle to said armature shaft, so that a forward movement of said handle causes said mechanism to impart an accelerated rotation to said armature to produce a spark for starting the engine, a high-tension running magneto operatively connected to the engine, and a switch mounted on the starting magneto and operated by the armature shaft thereof for controlling the high-tension circuits of the two magnetos.
10. In a dual magneto ignition system for gas engines, a high-tension starting magneto adapted to be operated by hand, a high-tension running magneto adapted to be driven by the engine, each magneto having a collector ring mounted on the armature shaft thereof, a distributor mounted on said running magneto and electrically connected to the spark plugs of the engine, said distributor having a rotary contact member driven in unison with the magneto shaft, an insulating block removably mounted on the starting magneto at the collecting end thereof and having a brush arranged directly in contact with the collector ring of said magneto, a first contact carried by said block and electrically connected with said collector brush, a second contact on said block in electrical connection with the collector brush of the running magneto, a third contact on said block in electrical connection with the rotary contact member of said distributor, a switch member slidably over said contacts for electrically connecting the first and third contacts to close the starting circuit and for electrically connecting the second and third contacts to close the running circuit, and a rotary disk on which said switch member is mounted.
11. In a dual magneto ignition system for gas engines, a high-tension starting magneto adapted to be operated by hand, a high-tension running magneto adapted to be driven by the engine, a distributor mounted on said running magneto and electrically connected to the spark plugs of the engine, said distributor having a rotary contact member driven in unison with the magneto shaft, an insulating block removably mounted on the starting magneto and having a brush arranged in contact with the collector ring of said magneto, a first contact carried by said block and electrically connected with said collector brush, a second contact on said block in electrical connection with the collector brush of the running magneto, a third contact on said block in electrical connection with the rotary member of said distributor, an insulating disk geared to the armature shaft of the starting magneto, and a switch member carried by said disk for electrically connecting the first and third contacts to close the starting circuit and for electrically connecting the second and third contacts to close the running circuit.
12. In a dual magneto ignition system for gas engines, a running magneto driven by the engine, a starting magneto, hand-operated means for oscillating the armature of the starting magneto to produce a single spark, circuit connections between said magnetos and the spark plugs of the engine, and a switch operated by the starting magneto for controlling the ignition circuits of the two magnetos.
13. In a dual magneto ignition system for gas engines, a starting magneto, an oscillating handle at one end of said magneto, operative connections between said handle and the armature shaft of said magneto for imparting an accelerated movement to the armature when the handle is thrown over, a switch operatively connected to said shaft, and a running magneto controlled by said switch.
14. In a dual magneto ignition system for gas engines, a starting magneto, a handle at one end of said magneto, driving connections between said handle and the armature shaft of said magneto, an insulating block mounted on said magneto and having a brush to collect current from the armature winding, contacts carried by said block, a rotary switch member mounted on the magneto frame and arranged to move over said contacts, means for operatively connecting said switch member to the armature shaft of the starting magneto, means for connect-

ing said contacts and switch member in the starting circuit, and a running magneto controlled by said switch, the ignition circuits of the two magnetos being independent of each other.

15. In a dual magneto ignition system for gas engines, a starting magneto, a movable handle at one end of said magneto, driving connections between said handle and the armature shaft of said magneto, a running magneto, circuit connections between said magnetos and the spark plugs of the engine, a switch in said circuit connections, and means for operating said switch in accordance with the movements of the armature shaft of the starting magneto, said switch automatically breaking the starting circuit and closing the running circuit when the handle is thrown forward, the return movement of the handle automatically operating said switch to open the running circuit.

16. In a dual magneto ignition system for gas engines, a running magneto, a starting magneto, circuit connection between said magnetos and the spark plugs of the engine, a movable handle, means whereby the forward movement of said handle operates the starting magneto, and a switch controlled by the forward movement of the handle to automatically break the starting circuit and close the running circuit after the operation of the starting magneto, the return movement of said handle automatically operating said switch to break the running circuit.

17. In a dual magneto ignition system for gas engines, a running magneto, a starting magneto, circuit connections between said magnetos and the spark plugs of the engine, a handle on the starting magneto, means whereby the forward movement of said handle operates the starting magneto, a switch mounted on the starting magneto and connected in the ignition circuits of the two magnetos, and means for controlling said switch in such a way that the forward movement of the handle automatically breaks the starting circuit and closes the running circuit after the operation of the starting magneto, the return movement of said handle automatically operating said switch to break the running circuit.

18. In a dual ignition system for gas engines, a high-tension starting magneto having a collector ring on the armature shaft, an insulating block removably mounted on the magneto frame over the collector ring, a collector brush and a plurality of contacts carried by said block, said collector brush being arranged to engage said collector ring, one of said contacts being electrically connected to said collector brush, another of said contacts being adapted to be electrically connected with a spark plug of an engine, an insulating disk mounted over the armature shaft and provided with a metallic strip ar-

ranged to move over said contacts, whereby said contacts and said strip constitute a high-tension switch for closing and breaking the high-tension starting circuit of the magneto, a gear on the armature shaft of said starting magneto, a gear connected with said disk and in mesh with said first-named gear, whereby the armature shaft operates said disk, and hand-operated mechanism to rotate the armature shaft for producing a starting spark, the rotation of said shaft moving said strip out of engagement with one of said contacts to break the high-tension starting circuit immediately after the moment of sparking.

19. In a dual ignition system for gas engines, a high-tension starting magneto having a collector ring on the armature shaft, an insulating block removably mounted on the magneto frame over the collector ring, a collector brush and a plurality of contacts carried by said block, said collector brush being arranged to engage said collector ring, one of said contacts being electrically connected with said collector brush, another of said contacts being adapted to be electrically connected with a spark plug of an engine, an insulating disk mounted over the armature shaft and provided with a metallic strip arranged to move over said contacts, whereby said contacts and said strip constitute a high-tension switch for closing and breaking the high-tension starting circuit of the magneto, and hand-operated spring mechanism mounted on the armature shaft of the magneto to impart an accelerated movement thereto for producing a starting spark, the rotation of said armature shaft moving said strip out of engagement with one of said contacts to break the high-tension starting circuit immediately after the moment of sparking.

20. In a dual magneto ignition system for gas engines, a high-tension running magneto, a high-tension starting magneto, circuit connections between said magnetos and the spark plugs of the engine, a spring-actuated switch, and circuit connections whereby said switch automatically closes the running circuit, after the starting spark has passed, before the next spark plug is to be fired.

21. In a dual magneto ignition system for gas engines, a high-tension starting magneto, hand-actuated mechanism for operating said magneto to start the engine, a high-tension running magneto operatively connected with the engine, a switch controlled by said mechanism for controlling the high-tension circuits of the two magnetos, and means whereby said switch, after the engine has started, closes the running circuit before the next spark plug is to be fired.

In a dual magneto ignition system for gas engines, a high-tension running mag-

adapted to be driven by the engine, a distributor mounted on said magneto and electrically connected to the spark plugs of the engine cylinders, said distributor having a rotary contact member driven by the magneto shaft, means for connecting said distributor in the high-tension circuit of the running magneto, a high-tension starting magneto electrically connected to the rotary contact member of said distributor, hand-actuated mechanism for operating the starting magneto, a switch for controlling the high-tension circuits of the two magnetos, and means whereby said switch, after the engine has started, closes the running circuit before said rotary member of the distributor is in position to connect the spark plug next to be fired.

23. In a dual magneto ignition system for gas engines, a high-tension starting magneto, hand-actuated mechanism for operating said magneto to start the engine, a high-tension running magneto operatively connected with the engine, said operative connections between the running magneto and the engine including a rotary distributor arm for successively connecting the spark plugs in circuit, a switch for controlling the high-tension circuits of the two magnetos, and means whereby said switch, after the engine has started, closes the running circuit before said distributor arm is in position to connect the spark plug next to be fired.

24. In a dual magneto ignition system for gas engines, a high-tension starting magneto, hand-actuated mechanism for operating said magneto to start the engine, a high-tension running magneto operatively connected with the engine, the high-tension circuits of the two magnetos being independent of each other, a switch controlled by said mechanism for controlling the high-tension circuit of the starting magneto, and means whereby said switch opens the starting circuit before the running magneto fires the next spark plug.

25. In a dual magneto ignition system for gas engines, a high-tension running magneto adapted to be driven by the engine, a distributor mounted on said magneto and electrically connected to the spark plugs of the engine cylinders, said distributor having a rotary contact member driven by the magneto shaft, means for connecting said distributor in the high-tension circuit of the running magneto, a high-tension starting magneto electrically connected to a spark plug, hand-actuated mechanism for operating the starting magneto, a switch operated by the armature shaft of the starting magneto, and circuit connections whereby said switch closes the starting circuit to start the engine while the running circuit is open and then automatically opens the starting circuit and closes the running circuit.

26. In a dual magneto ignition system for gas engines, a high-tension starting magneto, a handle movably mounted on the armature shaft of said magneto and capable of forward and return movement, spring mechanism for releasably connecting said handle to said armature shaft, so that a forward movement of the handle causes said mechanism to impart an accelerated rotation to said armature to produce a spark for starting the engine, a high-tension running magneto operatively connected to the engine, and a switch controlled by the armature shaft of the starting magneto for controlling the high-tension circuit thereof, said switch being adapted to open the starting circuit before the running magneto fires the next spark plug.

27. In a dual magneto ignition system for gas engines, a high-tension running magneto, a high-tension starting magneto, an oscillating handle at one end of said starting magneto, operative connections between said handle and the armature shaft of said starting magneto for imparting an accelerated movement to the armature when the handle is thrown over, a switch operatively connected to said shaft, and means for electrically connecting the starting circuit through said switch to a spark plug of the engine.

28. In a dual magneto ignition system for gas engines, a high-tension running magneto, a high-tension starting magneto, circuit connections between the running magneto and the spark plug or spark plugs of the engine, and means for connecting the starting circuit to a spark plug, said means including a switch adapted automatically to open the starting circuit before the running magneto fires the next spark plug.

29. In a high-tension ignition magneto, a spring connected at one end with the armature shaft of the magneto, an oscillating handle mounted on said armature shaft so as to move independently thereof, means for operatively connecting the other end of said spring with said handle, a device arranged to hold the armature shaft stationary when the handle is moved forwardly to wind up the spring, means for automatically causing said device to release the armature shaft when the handle has been moved a predetermined amount, whereby the armature receives accelerated rotation under the action of said spring, and a rotatable switch member operated by the rotating armature shaft to control the circuit of said magneto.

30. In a high-tension ignition magneto, an oscillating handle mounted on one end of the armature shaft of the magneto, spring mechanism for releasably connecting said handle to the armature shaft, so that a forward movement of the handle places said mechanism under tension and automatically

releases the same to impart accelerated rotation to the armature, said handle being free to be moved back to normal position, and a switch mounted on the magneto on the other end of the armature shaft and operated by said shaft to control the circuit of the magneto.

31. In an ignition magneto, a member fixed on the armature shaft, a casing rotatably mounted on the armature shaft, a handle fixed on said second member for turning the same, a spring in said casing connected at its ends to said members, a device for

holding the armature shaft stationary when the handle is moved to turn said casing whereby said spring is placed under tension, and means carried by said casing for actuating said device to release the armature shaft and thereby cause accelerated rotation thereof under action of the tensioned spring, 15 said handle being free to be moved back to normal position, and a rotatable switch member operated by the rotating armature shaft to control the circuit of the magneto.

FREDERICK W. ANDREW.
